Inventor

John H. Malin

UNITED STATES PATENT OFFICE.

JOHN H. MALIN, OF PERU, INDIANA.

EXHAUST OR DISCHARGE NOZZLE.

Application filed January 26, 1923. Serial No. 615,044.

To all whom it may concern:

Be it known that I, JOHN H. MALIN, a citizen of the United States, residing in the city of Peru, in the county of Miami and State of Indiana, have invented a new Exhaust or Discharge Nozzle, and have described the same in the following specification and illustrated by the accompanying drawings.

My invention relates to that class of exhaust nozzles used in locomotives to produce draft, and the discharge or exhaust ports in internal combustion engines. The main objects of this style of nozzle are:—in steam locomotives to prolong the life or use of the present nozzle tips or bushings, by being slotted as specified, if so desired; to increase the draft by assisting the expansion of the exhaust; to reduce the back pressure in the cylinders by increasing the area of the exhaust opening; to make the repairs on machinery and flues lighter; and to save fuel by a more even draft. In internal combustion engines, to reduce back pressure, to reduce the loud or sharp exhaust, and to save gas or fuel. To do this I make use of rectangular longitudinal slots extending the full length, of uniform width, and equally spaced apart, the number and size of which may vary according to result desired.

My drawings show the manner in which these slots are to be made. Figure 1 shows a plan view, while Figure 2 shows a cross-sectional view through the center. This nozzle is a cylindrical iron casting or hollow

shell, conforming to the opening in the cylinder casting or nozzle stand. A slot with walls as described, has a retaining power on matter or substance passing through, holding and retaining the volume in perfect and compact form from entrance to exit; the value of the slot is determined by the depth of the side walls as retaining power. A groove being a passage for substance or matter, and having no retaining power, the side walls being rounding or flaring, do not hold or retain matter to any particular or prescribed form. As compared with the nozzles now in use in locomotives this nozzle produces a greater contact with the gases in the smoke box because of the increased area of the opening resulting in a better and more uniform draft.

These slots permit a greater velocity of the exhaust steam or gases as the case may be by decreasing the resistance thereby causing a less violent or freer discharge.

I claim for my invention:

As an article of manufacture, an exhaust nozzle for locomotives and internal combustion engines, and the like, wherever back pressure is found, or a drafting force required, having a uniform bore from end to end, and having equi-distant longitudinal slots therein, of uniform depth, extending the full length of the nozzle, each of said slots having equal and parallel side walls, and a back wall at right angles thereto.

Witness my signature at Peru, Indiana.
JOHN H. MALIN.
